UNITED STATES PATENT OFFICE.

FREDERICK A. ANDREWS, OF PEQUANNOCK, NEW JERSEY, ASSIGNOR TO THE ESMOND MILLS, OF NEW YORK, N. Y., A CORPORATION OF MASSACHUSETTS.

DESIGN FOR A BLANKET OR SIMILAR ARTICLE.

Application filed August 21, 1922. Serial No. 3,494. Term of patent 7 years.

To all whom it may concern:

Be it known that I, FREDERICK A. ANDREWS, a citizen of the United States, residing at Newark Pompton Turnpike, in the village of Pequannock, Morris County, and State of New Jersey, have invented a new, original, and ornamental Design for a Blanket or Similar Article, of which the following is a specification, reference being had to the accompanying drawing, forming a part hereof.

The figure shown in the drawing is a face view of a folded blanket embodying my design, one corner of the blanket being folded back to disclose the reverse side of the blanket.

I claim:

The ornamental design for a blanket or similar article substantially as shown.

FREDERICK A. ANDREWS.
